UNITED STATES PATENT OFFICE.

ALBERT A. GRIFFIN, OF LANSING, MICHIGAN.

CHIROPRACTIC TABLE.

1,051,221.

Specification of Letters Patent. Patented Jan. 21, 1913.

Application filed July 2, 1912. Serial No. 707,400.

To all whom it may concern:

Be it known that I, ALBERT A. GRIFFIN, a citizen of the United States, residing at Lansing, in the county of Ingham and State of Michigan, have invented a new and useful Improvement in Chiropractic Tables, of which the following is a specification.

My invention consists of an improvement in the device disclosed in Letters Patent of the United States, No. 1029751, dated June 18, 1912 and issued to me for an improved chiropractic table, and its purposes are to improve the operation of the said table in use and to better adapt it for the various purposes for which such a device is employed. I attain these purposes by the means shown in the accompanying drawings in which—

Figure 1 is an elevation of my improved table taken from the side. Figs. 2, 3 and 4 are details illustrating various features of the construction.

The general construction and operation of my table is sufficiently set forth in the Letters Patent above referred to, and I will, only describe the novel features of my present application.

Referring to the drawings, 1 is the head portion of my table and 2 the foot, which in the present instance are shown supported on legs 3, but may be supported in any suitable manner, for instance, by box or panel sides as shown in the Letters Patent above referred to. If the supporting legs 35 are used they are preferably braced at the bottom and the head and foot portions kept at the proper distance from each other by longitudinally extending strips 4. The shelf 5, attached to the head portions of the table, 40 is substantially the same as in the above mentioned patent, except that I, at present, prefer to hinge it somewhat closer to the inner edge of the head portion, as, for example, at 6, as shown in Fig. 1. The toggle 45 7 and its brace 8 are also substantially the same as in the above patent, but the cross bar 10 is made narrower and the bar 8 simply passes over the top of it, engaging with the upper edge as shown in Fig. 1. A chain or other flexible stop 11 extends from the cross bar 10 to one member of the toggle 7, so as to prevent the toggle from straightening too much when the shelf 5 is raised. A plurality of springs 12, shown in plan view in Fig. 4 has one end of each spring 55 attached to the toggle 7 and the other end

to a lever 13, which has one extremity pivotally attached at 14 to the frame of the table and the other end free to pass along a bar 15, provided with pins 16 adapted to engage the lever 13, and thus permit any desired degree of tension to be placed upon the springs 12. It will also be noticed that by reason of the peculiar construction of the lever 13, the springs nearer the free end 60 of the lever are more affected by its motion, also that by a sufficient motion of the lever 13, the springs 12, which are located nearest to the movable end of the lever, might be relieved from all tension and instead left 65 hanging loosely so that when the lever was drawn from this position in the direction proper to tighten the springs, the springs would successively be placed under tension 70 after which time the tension would be increased gradually on all the springs, but most rapidly on those nearest the movable end of the lever. The result of this is to give a much wider range of tension to the springs than would be otherwise obtainable. 75 By the use of these springs any desired amount of lifting force can be applied to the shelf 5, which will thus furnish an elastic support of just the amount desired to the body when the patient is placed upon the 80 table and the brace 8 released.

In my improved table the brace 8 is controlled by levers 17. One of these levers is preferably mounted at each side of the shelf 5 as shown in Fig. 1. The levers themselves 90 are shown more fully in Figs. 2 and 3. Cords 18 extend from the extremities of each of these levers over pulleys 19 to the brace 8, which may thus be raised by pressure upward on the end 20 of either of the 95 levers, the two levers working independently of each other. Ordinarily but one of the levers will be used, the two being employed to make it convenient to operate the shelf 1 from either side of the table if desired. The levers 17 are sustained in the raised portion 100 by catches 21, shown in detail in Fig. 2. These catches are essentially simply bell crank levers, one extremity of which is adapted to support the end 20 of the levers 17 and the other to be moved by the finger. It is evident that when either of the catches 21 is operated, it will release the end 20 of the lever 17 and the brace will be permitted 105 to drop so as to engage with the cross bar 10 and support the shelf 5 in its raised position.

I have found it desirable to support the foot slide 22, shown in my previous construction as 15, by the use of a leg 23, provided with a caster 24, running on a track 25, which is parallel to the motion of the slide itself, thus serving to support the foot slide, without, in any way interfering with its action.

I claim as my invention and desire to secure by Letters Patent:-

1. In a table of the character described, the combination of a stationary head portion; a middle portion adapted to be raised and lowered; means for raising and lowering said middle portion; a plurality of springs acting upon said means in such a manner as to tend to raise said middle portion and means for successively applying tension to said springs.

2. In a table of the character described, the combination of a stationary head portion; a middle portion adapted to be raised and lowered; means for raising and lowering said middle portion; a plurality of springs acting upon said means in such a manner as to tend to raise said middle portion, and means for successively applying tension of said springs, said last mentioned means comprising a lever having one extremity of each of said springs attached to it intermediate its extremities, one extremity of said lever being pivotally attached to the frame of said table and the other being provided with a handle, and means for locking said lever in any desired position.

3. In a table of the character described, the combination of a stationary head portion; a middle portion adapted to be raised and lowered; a toggle for raising and lowering said middle portion; a plurality of springs acting upon said toggle in such a manner as to tend to raise said middle portion, and means for successively applying tension to said springs, said last mentioned means comprising a lever having one extremity of each of said springs attached to it intermediate its extremities, one extremity of said lever being pivotally attached to the frame of said table and the other being provided with a handle, and means for locking said lever in any desired position.

4. In a table of the character described, the combination of a stationary head portion; a shelf hinged to said head portion and to be raised and lowered; a toggle for raising and lowering said middle portion; a plurality of springs acting upon said toggle in such a manner as to tend to raise said middle portion, and means for successively applying tension to said springs, said last mentioned means comprising a lever having one extremity of each of said springs attached to it intermediate its extremities, one

extremity of said lever being pivotally attached to the frame of said table and the other being provided with a handle, and means for locking said lever in any desired position.

5. In a device of the character described, the combination of a foot portion supplied with a stationary top and having a movable slide adapted to form an extension to said top bridging the gap between said middle portion and said foot portion, and a leg attached to said movable slide so as to travel therewith.

6. In a device of the character described, the combination of a foot portion supplied with a stationary top and having a movable slide adapted to form an extension to said top bridging the gap between said middle portion and said foot portion; a leg attached to said movable slide so as to travel therewith, and a track upon which said leg travels.

7. In a device of the character described, the combination of a foot portion supplied with a stationary top and having a movable slide adapted to form an extension to said top bridging the gap between said middle portion and said foot portion; a leg attached to said movable slide so as to travel therewith; a wheel on the foot of said leg, and a track on which said wheel travels.

8. In a device of the character described, a head portion provided with a stationary top; a middle portion adapted to be raised and lowered; a toggle supporting said middle portion; a releasable lock for said toggle, and a releasable lock for preventing said first mentioned lock from acting when said shelf is raised.

9. In a device of the character described, a head portion provided with a stationary top; a shelf hinged to said top; a toggle supporting said shelf; a releasable lock for said toggle, and releasable means for preventing said lock from acting when said shelf is raised, said means comprising a lever operatively connected to said lock, and a second lever adapted to engage with said first mentioned lever so as to retain said lock in an inoperative position.

10. In a table of the character described, the combination of a stationary head portion; a middle portion adapted to be raised and lowered; means for raising and lowering said middle portion; a plurality of springs acting upon said means in such a manner as to tend to raise said middle portion and means for simultaneously varying the tension of said springs.

ALBERT A. GRIFFIN.
